UNITED STATES PATENT OFFICE.

WILLIAM V. GOODYEAR, OF HOUSATONIC, MASSACHUSETTS, ASSIGNOR TO MONUMENT MILLS, OF HOUSATONIC, MASSACHUSETTS, A CORPORATION OF MASSACHUSETTS.

DESIGN FOR A BEDSPREAD.

Application filed September 22, 1924. Serial No. 10,871. Term of patent 14 years.

To all whom it may concern:

Be it known that I, WILLIAM V. GOOD-YEAR, a citizen of the United States, residing at Housatonic, county of Berkshire, and State of Massachusetts, have invented a new, original, and ornamental Design for Bedspreads, of which the following is a specification, reference being had to the accompanying drawing, forming a part hereof.

The figure is a plan view showing a portion of a bedspread embodying my design.
The design shown in the upper left hand corner of the spread is repeated throughout the extent of the spread.

I claim:

The ornamental design for a bedspread, as shown.

WILLIAM V. GOODYEAR.
